UNITED STATES PATENT OFFICE.

RONALD F. McFEELY, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LASTING-MACHINE.

1,254,917.

Specification of Letters Patent. Patented Jan. 29, 1918.

Application filed December 18, 1913. Serial No. 807,476.

To all whom it may concern:

Be it known that I, RONALD F. McFEELY, a citizen of the United States, residing at Beverly, in the county of Essex and State 5 of Massachusetts, have invented certain Improvements in Lasting-Machines, of which the following description, in connection with the accompanying drawings, is a specification, like reference characters on the 10 drawings indicating like parts in the several figures.

This invention relates to controlling mechanism for lasting machines and particularly for machines of the type of the 15 hand method lasting machine, an example of which is illustrated in United States Letters Patent No. 584,744, granted June 15, 1897, to S. W. Ladd and R. F. McFeely. In machines of this type the instrumentalities 20 acting upon the work include the gripper, the tack driving devices and the edge gage which determines the distance from the edge of the shoe at which the tacks shall be driven. The gripper is used to seize and 25 pull the upper while lasting the shank, fore-part and toe of the shoe, but is not necessary for lasting the heel seat, the upper materials of which are simply wiped over upon the innersole and tacked. For advanta- 30 geous use the gripper must stand open ready to receive and seize the upper when the machine is started and it must be rendered inoperative while the heel seat is being lasted. Also the combined wiper and 35 tack carrier must at such time be retracted ready to advance to its work and be loaded with a tack when the machine starts. In lasting welt shoes small tacks are fully inserted to fasten the heel seat, and on other 40 parts of the shoe long tacks are left with their heads and stems projecting from the work for convenient withdrawal after the welt attaching operation. The raceway must be adjusted to supply short and long 45 tacks and the driver stroke must be regulated to obtain the desired full and partial insertion of such tacks. For expeditious use these adjustments should be correlated. The long tacks are inserted near the edge of the 50 shoe and the short heel seat tacks must be located more remotely from the edge but out of the way of the heel attaching nails.

By this invention controlling means is provided by which the several adjustments are correlated and provision is made for effecting these adjustments with a minimum loss of time and expenditure of energy by the machine operator. In the arrangement of the controlling mechanism and in the provisions for correlating the adjustments are 55 to be found important features of this invention which, together with certain more important combinations of parts and novel details of construction, will now be described with the aid of the accompanying 60 drawings and will then be pointed out in the claims.

Figure 1 is a side elevation of a hand method lasting machine equipped with controlling mechanism, built in accordance with 70 this invention, for the gripper, tack driver, tack raceway, and the edge gage by which the shoe is positioned to receive the tacks at different distances from the edge of the shoe bottom.

Fig. 2 is a perspective view of controlling devices for regulating the operation of the gripper updraw mechanism, the length of the driver movement, the position of the tack raceway and the position of the edge 80 gage.

Fig. 3 is a plan view of that portion of the mechanism shown in Fig. 1 which deals with the edge gage and the raceway.

Fig. 4 is a plan view of the controlling 85 devices for the updraw regulation.

Figs. 5 and 6 are respectively side and end elevations of the mechanism for controlling the work receiving positions of the gripper and the combined wiper and tack 90 carrier.

Figs. 7 and 8 are details showing the separate parts of the brake controlling mechanism.

The head of the machine is mounted on a 95 column in the foot of which is a power shaft bearing a driven pulley, a loose pulley and connecting clutch mechanism controlled by a treadle as in said patent. In the head of the machine is the cam shaft 5 to which is 100 fast its pulley 6 connected by a belt 8 to the loose pulley on the power shaft. The clutch treadle is connected with a brake releasing rod 10 encircled by a spring that normally

holds it depressed. The brake shoe 12, which is arranged to bear upon the inner face of the pulley rim as in Figs. 1, 5 and 6, is carried on a lever 15 fulcrumed on the 5 machine frame and normally upheld by a light spring 13 located under it. The brake is reversely moved by a cam 20 on shaft 5. The cam, through the brake, controls the work receiving position of the gripper and 10 the combined tack carrier and wiper. The cam has one high, brake-setting point and is adjusted to apply the brake at that point in the cycle of the machine at which the gripper is open and the tack carrier and wiper 15 is retracted. The cam acts downwardly through a roll 21 and collar 22 forming part of a vertical slide which is movably guided in the machine head and is upheld by a spring 19. The collar transmits motion 20 yieldingly through a spring 23 encircling the spindle 24 and thence through an adjustable foot 25, Fig. 1, which normally rests upon a slide 26 movable horizontally in the brake shoe 12 and held in place by a 25 retaining plate 28, Fig. 8. This slide has an opening into which the wedge-shaped end of the treadle-actuated rod 10 is movable to withdraw the slide from under foot 25 to release the brake, the slide being returned by 30 its spring 27 into the path of the brake setting cam 20 only after the treadle has been released. The spring 23 prevents a harsh action of the brake in case the clutch is not opened quite as soon as the brake is applied. In this construction it will be noted 35 that when the operator depresses the treadle to start the machine the slide 26 will be withdrawn from beneath the foot 25 thereby releasing the brake which will be lifted by the spring 13. The mechanism is now free 40 to be started by further depression of the treadle to set the friction clutch in the usual manner as will be apparent from the showing of Fig. 1. Through the friction clutch 45 the operator may now, by manipulating the treadle, cause the gripper to close and perform its lasting operations and may stop at any time required. This enables the operator to make sure that the stock is properly 50 lasted before allowing the machine to fasten the upper, complete its cycle and stop. This construction, therefore, gives the operator control of the machine during a substantial part of its cycle during which the lasting 55 operations of the machine are performed and provides means for automatically stopping the machine at a predetermined point in the cycle, for example, after the upper has been secured and the gripper has opened. 60 In a broad way this brake setting and releasing mechanism is of the type shown in my earlier United States Letters Patent No. 791,986 of June 6, 1905, but is an improvement thereon in some respects. No 65 claim is made herein to the particular con-

struction of this present mechanism, the right being reserved to cover that invention in a separate application.

The cam shaft 5 has gripper cams which include the updraw cam 30 having a path in 70 its front side face through which reciprocating motion is communicated to a slide 32 to raise the rear end of the updraw lever 35 and thereby lower the open gripper to stock receiving position. As herein shown 75 the gripper lowering force is transmitted through intermediate stops or devices 36, Figs. 2 and 4, which are normally held by a spring 37 in operative position between the lever and the slide 32, or a flange on the 80 slide, but are capable of separation and withdrawal from such position, as indicated in dotted lines, Fig. 4. When so withdrawn the slide 32 will reciprocate idly without lifting the adjacent end of lever 35 and the 85 gripper will be held up in an inoperative position, for heel seat lasting, by the stress of a spring 38 which acts downwardly upon the lever in the well-known way described in said first mentioned patent. 90

The tack driver 50 is raised by a cam and depressed by a spring as fully shown and described in said prior patent and stops or devices 56 which are also broadly like the corresponding parts in said patent are arranged between a collar 51 on the driver bar and the head through which the bar is guided to limit the descent of the driver and produce partial insertion of the tacks carried by the reciprocating wiper 60. The pair of driver stops or devices 56 have toothed connection with one another as do the pair of stops or devices 36 for the gripper and said pairs are connected together by a rod 55 as shown in Figs. 1 and 2 so that when the gripper stops 36 are retracted, and the gripper is consequently inoperative for heel seat lasting, the driver stops are also withdrawn and the driver makes its full stroke for full insertion of the heel 105 seat tacks. 110

The tacks are supplied to the tack carrier and wiper 60 by a double raceway 65 which is shiftable sidewise to present its long tack carrying groove and its short tack carrying 115 groove alternatively to the tack separating mechanism 70 by which the tacks are taken one at a time from either raceway and delivered to the tack carrier, as is well understood in the art. This adjustment of the 120 raceway is made by a rod connection 61 with a stud 68, Figs. 2 and 9, mounted eccentrically in a pinion 66. The pinion 66 on a shaft 59 is turned by a segment 67 on a vertical shaft 69 connected with the rod 125 55 which connects together the driver stops and the gripper stops. This vertical shaft has a hand lever 78 by which it can be turned and caused to effect simultaneous adjustment of the raceway to provide small tacks, the 130

- driver stops to allow full insertion of such tacks, and the gripper stops to discontinue the effective operation of the gripper. Reverse adjustment of the vertical shaft makes 5 the opposite adjustments of said parts suitable for side and forepart lasting. If no tacks are desired, as when binding toes with wire, an eccentric 73 mounted on the stud 68 can be turned by its handle 63, Fig. 2, to 10 locate the raceway with its grooves midway between positions for delivering tacks from either of them. The eccentric 73 is held in either position of adjustment by a spring pin 76 Fig. 9.
- 15 The position of the edge gages 79, 80 is also controlled by adjustment of the vertical shaft 69. For this purpose the shaft 59 on which the pinion 66 is mounted has an eccentric connection 77, Figs. 3 and 9, with a 20 link 71 that extends backwardly to a lever 72. One end of the lever has an adjustable pin and slot connection 74 with a portion of the machine head, and the other end of the lever is connected to an edge gage carrier 75 25 which is mounted to slide from front to back on a guide rib on the lower face of the machine head. These parts are organized so that when adjustment of the controlling devices is made by means of vertical shaft 69 30 to withdraw controlling devices 36 and 56 for suspending the operation of the gripper and providing full insertion of the heel seat tacks the gage carrier 75 is retracted or moved inwardly toward the body of the 35 machine to allow for the insertion of the heel seat tacks inside of the location for the heel attaching nails. The extent of the movement imparted to the edge gage for this purpose can be varied by the pin and slot 40 connection which the link 71 has with the lever 72 and the normal position of the edge gage carrier can be varied to suit different conditions by the adjustable connection 74.
- In addition to the forth and back adjustment of the gage carrier the usual thick edge gage 80, which is used while lasting the heel seat but is in the way while lasting the shank because it is too thick to reach 45 into the shanks of many styles of shoes, is connected with the controlling mechanism so that it is brought up into position for use when adjustment of the other parts is made for heel seat lasting and is turned down out of the way when adjustment of 50 the gripper, tacking devices, etc., is made for shank and side lasting, the thin edge gage 79 remaining in operative position. For this purpose the vertical shaft 69 is connected by a crank arm 81 and link 82, Figs. 55 2 and 3, with a toothed segment 84 which drives a rack 85. The rack meshes with the pinion 86 secured to a pivot pin mounted in the front end of the gage carrier 75 and upon which the thick gage 80 is fastened. 60 By these connections the thick edge gage is turned up and down by movement transmitted from the vertical shaft 69.
- In the use of a machine of this invention, an operator will start lasting a shoe at one side of the shank as is the custom. For 70 this purpose he will find the machine at rest with the wiper and tack block retracted to permit proper presentation of the shoe in the machine and the gripper jaws open for the reception of the upper, these conditions having been provided for by the controlling devices 12, 20 when the machine was last brought to rest. A single adjustment of the vertical shaft 69 and the controlling devices connected therewith will 75 now position all of the operating parts suitably for lasting the shank by locating the gripper stops 36 in position to cause the gripper to operate, by locating the driver stops 56 in position to leave the tacks 80 standing for subsequent withdrawal after the welt attaching operation, by shifting the raceway to cause it to furnish long tacks required for shank and side lasting, and by turning the thick edge gage down out of the 85 way of the shoe and advancing the edge gage carrier 75 to cause the thin edge gage to position the shoe for locating the tacking line in desired proximity to the edge of the 90 shoe bottom. The improvements provided by this invention save the time of the operator required to make the separate adjustments necessary for machines as heretofore built. When the side lasting is completed 95 and the heel seat lasting is to be commenced, the machine will again come to rest with the tack block and wiper in retracted position and the gripper upraised with its jaws open. A single adjustment of the vertical shaft 100 69 in the direction reverse to that in which it was previously turned will now withdraw the gripper stops 36 from under the updraw lever so that the updraw cam and its slide will therefore fail to lower the gripper to upper seizing position and the gripper 105 will remain upraised out of the way of the operator during the heel seat lasting. Simultaneously with this adjustment the stops 56 will be withdrawn from the tack driver, permitting the driver to make the length 110 of the stroke for full insertion of the heel seat tacks. The raceway will be shifted to deliver short heel seat tacks; the gage carrier 75 will be retracted for positioning the tacks inside the line of heel nails and the 115 thick edge gage will be swung upwardly into operative position. The expedition with which the required adjustments can be made and the certainty that the machine will always position the wiper and tack block 120 and the gripper in readiness for receiving the work so that the first cycle of the machine can always be utilized, as herein provided for, enables this invention to increase 125 the capacity of the machine.
- 130

Having explained the nature of this invention and described a preferred construction embodying the same, I claim as new and desire to secure by Letters Patent of the 5 United States:

1. A machine of the class described having, in combination, a gripper, means for imparting to the gripper updraw movements including a continuously running 10 cam, an updraw lever and a slide for transmitting movement from the cam to the lever, a driver and means for reciprocating it to insert upper fastening tacks, and connected controlling means for discontinuing operative 15 connection between the updraw lever and the continuously running cam and for regulating the length of stroke of the driver.

2. A machine of the class described having, in combination, an upper stretching 20 gripper, upper fastening mechanism, and operating mechanism for imparting updraw movements to the gripper comprising a cam and connections therefrom to the gripper including a motion transmitter which is 25 bodily movable to discontinue completely the updraw movements of the gripper.

3. A machine of the class described having, in combination, a gripper, means for imparting to the gripper updraw movements, including a continuously running cam, an updraw lever, and a slide for transmitting movement from the cam to the lever, a double raceway for supplying tacks of different sizes, a driver and continuously 35 running means for reciprocating it to insert tacks to secure the upper stretched by the gripper, and connected controlling means for discontinuing operative connection between the updraw lever and the continuously running cam and for shifting the raceway to supply to the driver tacks of a 40 different size.

4. A machine of the class described having, in combination, an upper stretching 45 gripper, upper fastening mechanism and operating mechanism for the gripper comprising an updraw lever, a cam, a slide moved by the cam, devices adapted to occupy a position between the lever and the slide for transmitting movement, and means for withdrawing said devices from position where they will transmit such movement.

5. A machine of the class described having, in combination, an upper stretching 55 gripper, upper fastening mechanism and operating mechanism for the gripper comprising a cam, a lever, a slide adapted to lift the adjacent end of the lever, means for yieldingly depressing said adjacent end of the lever, devices through which the slide 60 uplifts the lever and which are removable from position for performing their function, power mechanism for driving the cam, and means arranged to stop the cam with 65 the adjacent end of the lever under control

of the said yielding means and in position to permit the withdrawal of said devices.

6. A machine of the class described having, in combination, an upper stretching gripper, upper fastening mechanism, operating mechanism for raising and lowering the gripper, means arranged for adjustment when the gripper is raised to render inoperative the mechanism for lowering said gripper, and means arranged to stop the machine 70 always with the gripper upraised to facilitate the adjustment of said first-mentioned means while the machine is at rest.

7. A machine of the class described having, in combination, an upper stretching 80 gripper, upper fastening mechanism, operating mechanism therefor, an edge gage arranged for sliding adjustment to alter the position of the fastenings relatively to the shoe edge, a second edge gage mounted on the gage for adjustment into and out of operative position relatively thereto, and connected mechanism for effecting adjustment of the two gages together relatively to the shoe edge and adjustment of the second gage 90 into and out of operative position.

8. A machine of the class described having, in combination, an upper stretching gripper, upper fastening mechanism, an edge gage adjustable to position the shoe 95 for the reception of tacks at different distances from the edge of the shoe bottom, tack supplying mechanism arranged to deliver tacks of different sizes and connections between the gage and said supplying mechanism arranged to cause the latter to deliver tacks of one size when the gage is positioned to locate the tacks at one distance from the shoe edge and to deliver tacks of a different size when the gage is positioned to locate the tacks at a different distance from the shoe edge, said connections having provision 100 for adjustment of the gage to provide for differently locating the limits of movement of the gage.

9. A machine of the class described, having, in combination, an upper stretching gripper, tack fastening mechanism and means to position the shoe for the reception of tacks in the desired relation to the edge 115 of the shoe bottom, said means comprising a thick edge gage adapted for use in lasting the heel seat and a thin edge gage for use in lasting the shank, and connected means for adjusting the shoe positioning mechanism to present for use either the thin or the thick gage and for adjusting the tacking mechanism to make full insertion of the tacks when the thick edge gage is in operative use and to make a partial insertion of the tacks when the thick edge gage is out of operative position.

10. A machine of the class described having, in combination, an upper stretching gripper, tack driving mechanism and means 120

- to position the shoe for the reception of tacks in the desired relation to the edge of the shoe bottom, said means comprising a thick edge gage adapted for use in lasting the heel seat and a thin edge gage for use in lasting the shank, stops arranged for movement into and out of relation to the tack driver to limit the descent of the driver and means connecting the thick edge gage and said stops to withdraw said stops when the thick edge gage is moved into operative position and to insert said stops when the thick edge gage is moved into inoperative position. 5
- 10 11. A machine of the class described having, in combination, an upper stretching gripper, tack fastening mechanism and means to position the shoe for the reception of tacks in the desired relation to the edge of the shoe bottom, said means comprising a thick edge gage adapted for use in lasting the heel seat and a thin edge gage for use in lasting the shank, devices adapted for adjustment to discontinue the operation of the gripper and means connecting said devices and the thick edge gage and arranged to render the gripper inoperative when the thick edge gage is in operative position and vice versa. 20
- 15 12. A machine of the class described having, in combination, an upper stretching gripper, tack fastening mechanism, shoe positioning means adjustable to locate the shoe for the reception of tacks at different distances from the edge of the shoe bottom, devices adapted for adjustment to render the gripper inoperative and means connecting said devices and said positioning means to render the gripper inoperative when the positioning means is adjusted to locate the shoe for the reception of tacks at a 25 different distance from the edge. 30
17. A machine of the class described having, in combination, an upper stretching gripper, tack fastening mechanism, shoe positioning means mounted for adjustment to locate the shoe for the reception of side lasting tacks near the edge of the shoe bottom and for the reception of heel seat tacks at a different distance from the shoe bottom, devices adapted for adjustment to render the gripper inoperative, and means connecting said devices and said positioning means and operating to render the gripper inoperative when the positioning means is adjusted for heel seat lasting. 50
18. A machine of the class described having, in combination, upper stretching gripper, means adapted for adjustment to render said gripper operative or inoperative, upper fastening mechanism including a driver and a double raceway, means for regulating the stroke of the driver to provide for full or partial insertion of tacks, means for adjusting the raceway to cause it to supply short or long tacks, positioning means arranged to locate the shoe for the reception of tacks at different distances from the edge of the shoe bottom and connected means for simultaneously controlling the different adjustments of the gripper, the driver, the raceway, and the shoe positioning means. 75
19. A machine of the class described having, in combination, an upper stretching gripper, tack driving mechanism, a thin edge gage, a thick edge gage arranged to swing into and out of operative position, tack supplying mechanism arranged to deliver long and short tacks, and connected means for effecting the delivery of short tacks, retraction of both gages, and the movement of the thick edge gage into operative position. 80
20. In a machine of the class described, the combination of an upper stretching gripper, upper fastening mechanism, a support, and two edge gages mounted upon the support, one of said gages being arranged for movement into and out of operative position and the other constructed and arranged to be advanced and retracted by connection with the first as it is moved into and out of operative 85 position. 90
21. In a machine of the class described, the combination of an upper stretching gripper, upper fastening mechanism, a support, two edge gages mounted upon the support, one of said gages being arranged for movement into and out of operative position and the other constructed and arranged to be advanced and retracted by connection with the first as it is moved into and out of operative 95 position, and means permitting adjustment of the support to vary the advanced position of the gages. 100
22. In a machine of the class described, the combination of an upper stretching gripper, a driver, driver stroke changing mechanism, a thin edge rest, and a thick edge rest, and controlling means constructed and arranged to retract the thin edge rest to move the thick edge rest into operative position 105 and to change the stroke of the driver to effect full insertion of the tacks. 110
23. In a lasting machine of the step-by-step type, the combination with power operated lasting mechanism and automatic means for stopping the machine at a given point in its cycle, of means for effecting manual control of the lasting mechanism during the greater portion of the cycle. 120
24. In a lasting machine, the combination 125 of lasting mechanism, power means for operating the lasting mechanism to do its work, manually controlled means for effecting the operation of the lasting mechanism and upper securing means, and automatic means 130

- for stopping the machine after the upper securing operation.
21. In a lasting machine, the combination of lasting mechanism, power means for operating the lasting mechanism to do its work, manually controlled means for operating the lasting mechanism and upper securing mechanism, and means operating automatically to stop the machine after the upper securing operation if the machine is left to itself.
22. A step-by-step type of lasting machine having a gripper, means for actuating the gripper repeatedly in continuous operation of the machine, means to stop the machine automatically at the end of its cycle, and means for manually controlling the operation of the gripper during the major portion of the cycle.
23. A step-by-step type of lasting machine having a gripper, means for actuating the gripper repeatedly in continuous operation of the machine, upper securing mechanism, and means for stopping the machine automatically if desired after the operation of the securing means, and means under the control of the operator for effecting or arresting operation of the gripper at the will of the operator until the end of the cycle is approached.
24. A machine of the class described having, in combination, an upper stretching gripper, means for operating the gripper to do its work, upper fastening mechanism, a treadle and friction clutch for controlling the operation of the gripper, a brake, means for tripping off the brake by initial movement of the treadle leaving the gripper under control of the operator through the friction clutch until approximately the end of the cycle, and means operating if the treadle is released after the upper is stretched and fastened to set the brake and stop the machine at the end of the cycle.
25. A machine of the class described having, in combination, an upper stretching gripper, means for operating the gripper including a treadle, and a friction clutch for controlling its operation, a brake, means operated by initial movement of the treadle to trip off the brake leaving the gripper under control of the operator for the greater portion of the cycle through the treadle and friction clutch to operate the gripper first to grip the stock and to then operate it to stretch the stock, and means operating automatically to stop the machine when the grippers again open if the treadle is released.
26. A machine of the class described having, in combination, an upper stretching gripper, mechanism for operating the gripper to do its work, a manually controlled friction clutch whereby the machine may be run or stopped during the major portion of its cycle, and means becoming operative when the friction clutch is released and the machine is running under its own momentum for automatically stopping the machine at a given point in its cycle.
27. A machine of the class described having, in combination, an upper stretching gripper, mechanism for operating the gripper to do its work, a friction clutch, a treadle whereby the machine may be run or stopped during a portion of its cycle, a brake, cam-operated means for setting the brake at a given point in the cycle, and means for preventing the operation of the cam on the brake until the power operation is released, said cam then acting under the momentum of the machine to set the brake to stop the machine at a given point in the cycle.
28. In a lasting machine, a gripper, operating means to open and close the gripper, a brake, a treadle, a friction clutch controlled by the treadle, means for tripping off the brake at the beginning of the cycle and permitting operation by the friction clutch during the major portion of the cycle to control the gripper, and mechanism coming into operation only when the treadle is released to set the brake and stop the machine at the end of a cycle with the gripper open.
29. A machine of the class described having, in combination, an upper stretching gripper, tack driving mechanism, a thin edge gage, a thick edge gage, interconnected mechanism constructed and arranged to act, when in one position, to locate the thin edge gage for driving tacks near to the shoe edge and, when in another position, to locate the thick edge gage for driving tacks at a greater distance from the shoe edge, and means operated by said interconnected mechanism for controlling the supply of tacks to the driving mechanism in such manner as to insure that short tacks will be driven when one edge gage is in use and long tacks when the other gage is in use.
